E. B. NOWOSIELSKI

BINDING POST FOR ELECTRIC CABLES

Filed Sept. 24, 1920

INVENTOR
Edward B. Nowosielski
BY
Albion D. T. Lebby
ATTORNEY

UNITED STATES PATENT OFFICE.

EDWARD B. NOWOSIELSKI, OF NEWARK, NEW JERSEY, ASSIGNOR TO SPLITDORF ELECTRICAL COMPANY, OF NEWARK, NEW JERSEY.

BINDING POST FOR ELECTRIC CABLES.

Application filed September 24, 1920. Serial No. 412,441.

To all whom it may concern:

Be it known that I, EDWARD B. Nowosiel-
ski, a citizen of the United States, residing
at Newark, in the county of Essex, State of
5 New Jersey, have invented certain new and
useful Improvements in Binding Posts for
Electric Cables, of which the following is
a description, reference being had to the
accompanying drawing and to the figures of
10 reference marked thereon.

My invention relates to binding posts for
electric cables, more particularly those used
in connection with ignition apparatus.

The object of my invention is to provide
15 a quick detachable binding post of this
type.

A further object is to provide a binding
post of this type which permits of quick
assembly of the cable and the terminal.

20 Another object of this invention is to
provide a cheap and efficient binding post
of the quick detachable type.

Other objects will appear to those skilled
in the art from the following description
25 and accompanying drawings, in which—

Figure 1 is a longitudinal sectional view
through the binding post, showing the
cable in place and the binding post mounted
ed on a frame, and

30 Figure 2 is a plan view of my binding
post, the cable being inserted in place.

My binding post consists of two threaded
main portions, a male member 1 threaded
at 2 and provided with an enlarged portion
35 threaded at 3 and a female member 4 hav-
ing a bore threaded at 5, both of high ten-
sion insulation material. Moulded within
the male member is a roughened metallic pin
6 made of steel or other suitable hard con-
ductive material, the end of this pin being
40 turned down to a smaller diameter as at 7
and tapered to a stiletto point as shown in
dotted lines in Figure 1.

The female member has a bore 8 at an
45 angle to the first mentioned bore extending
through the major portion of the length
of the member into which an insulated cable
17 having a preferably stranded conductor
18 may be inserted.

50 A hole 9 in a partition wall 19 between
the bores is provided for the reception of
the point of the pin. The partition 19 is
shown moulded integral with the member 4,
thereby forming a barrier of insulating ma-
55 terial to prevent the high tension current

from the conductor 18 jumping out to the
mounting plate 13, which it would have a
tendency to do through the joint produced
by the threads 3 and 5, if the partition
were not present. The lower portion of the 60
member 4 is channelled as at 10 and a soft
rubber bushing provided with a beaded edge
12 is slipped over the member 4 so as to ren-
der the binding post dust and moisture
65 proof when the cable is in place. The male
member is clamped to its support as to the
framework 13 of a magneto by means of a
washer 14 and locknut 15. A quill ter-
70 minal 16 as from the secondary of an induc-
tion coil abuts a slightly hollowed out part
of the pin 6 when the male portion of the
binding post is in place.

In assembling the two parts of the bind-
ing post, the male member being mounted
in place on the magneto frame, the cable 75
is first inserted in the bore 8 until it seats
against the bottom of the bore then the
female member is threaded onto the male
member, with the tapered portion of the
pin extending through the hole. It is pref-
80 erable that the cable fits snugly within the
bore, so that when the tapered pin pene-
trates the cable, the spreading of the cable
will cause it to be bound tightly against the
wall of the bore. As the two members are
85 screwed together, the tapered pin pierces
the insulation of the cable and engages the
conductive wire therein. Thus a quick and
good electrical connection is assured by the
mere screwing on of the member 4.

Having thus described my invention what
I claim is:

1. A quick detachable binding post com-
prising a female member provided with a
cable receiving bore, another bore at an
angle to the same, a partition separating
said bores, said partition being formed in-
tegral with the female member, an end be-
ing provided with a centrally located aper-
ture, a male member of insulating material
fitting snugly into the last mentioned bore,
a tapered conducting pin embedded within
said male member and passing through the
aperture in the partition, said male mem-
ber having an extension to receive and sup-
port a conductor in end to end contact with
said tapered pin as and for the purpose
described.

2. A quick detachable binding post com-
prising a one-piece female member provided

105

110

with a cable receiving bore, another bore at an angle to the same, a partition separating said bores, said partition being formed integral with the female member and provided with a centrally located aperture, a male member of insulating material screw threaded into the second mentioned bore, said male member having an extended part with a bore therein, a conducting pin moulded in the male member closing one

end of the bore therein, said pin having a tapered end passing through the aperture in said partition into contact with said cable in the female member, said bore in the male member serving to support a conductor in end to end contact with said pin. 15

In testimony whereof, I affix my signature.

EDWARD B. NOWOSIELSKI.
